CONCENTRATING TABLE AND METHOD.

1,423,777.

Specification of Letters Patent. Patented July 25, 1922.

Application filed November 23, 1920. Serial No. 426,055.

To all whom it may concern:

Be it known that we, VICTOR F. NEWMAN and MERTON W. LOOMIS, citizens of the United States, and residents of Red Cliff, 5 in the county of Eagle and State of Colorado, have invented a new and Improved Concentrating Table and Method, of which the following is a description.

Our invention relates to a concentrating 10 table in which concentration and stratification are effected essentially by hydraulic settling of wet ground material and with which wash water is employed only to wash off the middlings from the stratified material after the elimination of the tailings.

General objects of our invention are to provide a concentrating table radically improved in various particulars, whereby to embody certain features to cause the table to 20 concentrate and save not only the coarsely ground particles of the valuable portion of ores but also save to the maximum extent the very fine particles of the values or "slimes" as they are generally termed.

25 The invention also has for an important object to provide a concentrating table that will effect the concentration by hydraulic settling and which will not require any sizing of the material to be treated.

30 A further object of the invention is to provide a concentrator that will use a comparatively small portion of the power usually expended in the operation of similar apparatus as well as to provide a compact 35 apparatus occupying approximately half of the space of the usual apparatus and characterized by requiring the use of a small quantity of wash water.

Other objects of the invention will be apparent as the description proceeds.

Reference is to be had to the accompanying drawings forming a part of this specification, it being understood that the drawings are merely illustrative of one example 45 of the invention.

Figure 1 is a plan view of a concentrator table embodying our invention;

Figure 2 is a longitudinal vertical section on the irregular line 2-2, indicated in 50 Figure 1;

Figure 3 is a partly sectional perspective view of a portion of the table, the section being indicated by the line 3-3, Figure 1;

Figure 4 is an enlarged detail in trans- 55 verse vertical section, the view being given to more clearly show the manner in which

the material is stratified in its advance over the table;

Figure 5 is a detail in transverse vertical section given to show a form of table support that may be employed, the section being taken in a plane corresponding with the line 5-5 in Figure 2;

The table is of the bumping type and while the vibration may be carried out in 60 various ways, features of the illustrated form are advantageous. In the example shown the table 10 is suspended in a frame designated generally by the numeral 11, the numeral 12 indicating sails. The table is generally of triangular form and supported at 65 three points for which purpose in the illustrated example standards are provided at three points, there being a pair of standards 13 at the broad or feed end of the table and a single standard 13 at the narrow end of the table. Various expedients may be employed for suspending the table 10 from the upper ends of the standards 13, 13^a. In the form shown a cross bar 14 is provided at 70 the feed end of the table extending between the standards 13 and as here shown said cross bar is rockably supported on trunnions 15 turnably mounted in said standards. A vertical screw rod 16 extends through the 75 bar 14 adjacent to each end thereof and extends at its lower end through a lug 17 on the table 10, the lugs resting on the heads 16^b of the screw. A nut 18 on the screw above the bar 14 serves to adjust the table 80 and retain it at any given height. At the narrow end a similar arrangement is provided, there being a short block 14^a having a trunnion 15^a in the adjacent standard 13^a and a screw 16^a corresponds with the screw 85 16 and extends through a lug 17^a on the table, the screw being provided with a nut 18^a.

The means shown for vibrating the table consists of a cam shaft 19, adapted to be 100 driven in any suitable manner, there being shown a belt pulley 20 adapted to receive power from any convenient source (not shown). The cam 19^a on the shaft 19 is adapted to wipe against a vertical wall or 105 member 21 rigid with the table 10, said member being provided, if desired, on a casting 22 in which the cam turns. At the opposite side of the cam wall or member 21 the table is engaged by a vertical plate 110 spring 23 fast at its upper end on the cross bar 14, its lower end lying adjacent to the

wall or vertical member 24 of casting 22. The arrangement is such that as the cam 19^a by engaging the member 21 moves the table in one direction the spring 23 is stressed so that it may re-act when the cam 19^a cams off the upper end of the member, 21. Thus, the cam moves the table in one direction while the spring 23 returns it after release by the cam.

10 The casting 24 may be let into a longitudinal beam 25 at the under side of the table 10, the opposite end of said beam constituting a bumper bar; for the purpose it is provided with a bumper head 26 and narrowed as at 15 27 adjacent to said head, a bumper block 28 being provided in front of the head 26 to receive the impact of the bumper bar or beam. Suitable guide means is provided for the reciprocating movement of the bumper beam, 20 there being shown a guide block 29 spaced from the standard 13^a, sufficient to accommodate said beam.

The table 10 operates to concentrate and stratify the material by the jarring of the 25 table and without the use of washing water and a clarifier is employed beyond the narrow end of the table for washing off the middlings from the stratified material. The triangular form of the effective area of the 30 table may be given to it by providing a barrier or rail 30 at one side parallel with the axis of the table or approximately so while the opposite side of the table has an oblique rail or equivalent barrier 31 and there may 35 be employed a corner strip 32 on the table adjacent to the oblique rail 31.

The concentrating riffles 33 are disposed oblique to the parallel rail 30 of the table, an effective angle being 25° to said rail and 40 to the longitudinal axis of the table, the oblique barrier 31 having a corresponding angle to the axis. Thus the riffles 33 are at an angle of approximately 50° to the oblique side of the table and are so disposed as to 45 extend from points along the transverse feed end of the table and then along the parallel rail 30, said riffles being disposed generally toward the oblique barrier 31. The angle of 50° applies to the main riffles 33 distributed over the major portion of the 50 table area; adjacent to the narrowed end of the table advantageously, the riffles (33^a) have a decreasing angle, being approximately 40° in practice. The riffles 33 terminate short of the oblique side 31 and thereby 55 a longitudinal passage 34 is provided on the table between said oblique side 31 and the ends of the riffles 33 along which passage the stratified material after leaving the riffles 60 33 is advanced toward the narrow end of the triangular table. Riffles 33, 33^a are of uniform height.

The tailings are discharged at the straight side of the table from approximately the 65 transverse center of the table to the nar-

rowed end thereof. An incline 35 over which the tailings escape may be provided, together with any suitable means for conducting them to any desired point. The tailings are crowded off the table by reason of the triangular shape of the table and I avoid thereby use of wash water to give movement to the tailings, and thereby eliminate the losses due to the carrying off of the "slimes" by the wash water.

70 A clarifier designated generally by the numeral 36 which is provided beyond the narrower end of the triangular concentrating area presents a surface continuous with that of the concentrating table and it extends laterally beyond the straight side 30 of the table, there being provided an incline 35^a for the tailings at the rear of the laterally extending portion of the clarifier 36 and co-terminous with the incline 35 which is parallel with the straight side 30. Between the feed end of the table and the tailings discharge 35 the straight side 30 rises to a height that will prevent the escape of tailings until their discharge is permitted at a 80 point where the separation of the values has progressed to the desired extent.

85 By the described arrangement the material will become stratified between the riffles 33 with the fine concentrates at the bottom as at 90 *a*, the coarser concentrates in a stratum *b*, next above, the middlings next above the coarse concentrates as indicated at *c*, and the tailings *d* at the top, all as conventionally indicated in Figure 4, the tailings moving 95 forwardly and laterally in the form of a gentle surface wave and the middlings having similarly a wave form in advancing; the middlings, however, moving in a resultant direction which will deliver them beyond 100 the tailings discharges 35, 35^a so that they may be washed off at the clarifier 36.

105 The accumulating accretions discharged by successive concentrating riffles 33 to the oblique passage 34, together with the vibration of the table, causes the stratified material to be progressed toward the narrowing discharge end of the table with a gentle but comparatively rapid movement without disturbance of the stratification. Also, the angular disposition of the concentrating riffles 33 relatively to the oblique side or rail 31 and to the oblique passage 34, is such as to cause a discharge from the riffles to said 110 passage gently and without disturbance of the stratification effected in the settling of the materials between the riffles, the settling progressing along said oblique passage.

115 It will be observed that the riffles 33 are shown bevelled at the discharge side, while the receiving side or that side toward the oblique rail 31, is perpendicular to the table surface or approximately so. Preferably, the beveling is on transverse lines presenting a compound curve. The described form 120 125 130

and uniform height of the riffles 33 together with the angular positions of the riffles factors in bringing out the stratification in causing the tailings forming the top stratum 5 of the separated material to move forwardly and laterally in the form of a gentle wave and making for the maximum tendency of the materials to settle in strata with the fine values at the bottom as referred to. In this 10 way the fine values are saved to the maximum extent while the tailings are effectively carried forwardly and laterally without the employment of washing water which is recognized as tending to carry off the finer 15 particles of the values.

In the movement of the materials between the riffles 33 and along the passage 34 the middlings are finally disposed at the top as the stratified material reaches the clarifier 20 36. The clarifier has a discharge 37 at the end and it is provided on the surface with riffles 38 and said riffles are disposed in the general direction of the discharge 37 for the concentrates and at a gradually less angle 25 from that side adjacent to the oblique rail 31 to the opposite side. The middlings at the clarifier are washed off with water supplied at the side adjacent to the rail 31, there being indicated for the purpose a supply 30 pipe 39 adapted to be connected with a source of water supply and delivering to a distributing box 40 from which a plurality of oblique outlets 41 discharge rearwardly or in the general direction of the on-coming 35 concentrates into a reservoir 42 extending longitudinally of the clarifier, the water finally escaping over a wall 43 constituting a break-water to prevent a too violent movement of the water against the material. The 40 water flowing over the wall 43 transversely of the clarifier surface and over the successive riffles 38 gently washes off the middlings which pass over an incline 45 at the discharge side of the clarifier. The middlings 45 in practice may be collected in any suitable manner to be again subjected to the concentrating process.

The material is fed to the concentrating table adjacent to the oblique side so that it 50 will be required to travel forwardly over the table a considerable distance before the lateral movement of material causes the tailings to discharge. We have shown a box-like structure 46 and a feed pipe 47, the surface 55 of said receiver 46 being continuous with the surface of the table 10. In practice, the table preferably is built up of narrow boards or strips 10^a over which is a covering 10^b of oil-cloth or the like on which the concentrating 60 riffles 30 are secured.

It will be observed that there is an unriffled feed-distributing area 10^c on the table of general triangular form between the riffles 33 and the feed device 46.

65 Certain of those riffles 33^a adjacent to the

narrowed end of the table terminate short of the others, to increase the effective width of the longitudinal oblique passage adjacent to the point of delivery of the washing water.

70

We would state in conclusion that while the illustrated example constitutes a practical embodiment of our invention, we do not limit ourselves strictly to the mechanical details herein illustrated, since manifestly the 75 same can be considerably varied without departure from the spirit of the invention as defined in the appended claims.

Having thus described our invention, we 80 claim:

1. In a concentrating apparatus, means to stratify the material without wash water, and clarifying means by which the stratified material is received from the first means.

2. A concentrating apparatus including a 85 hydraulic settling means to concentrate and stratify the material, and clarifying means to which the stratified material is fed by the first means, said second mentioned means comprising means to direct water to the 90 clarifier to wash off the upper stratum of the material.

3. A concentrating apparatus including a hydraulic concentrator for stratifying the material with the fines at the bottom and 95 the middlings at the surface, said hydraulic concentrator having a tailings discharge; and means to wash the upper stratum of middlings from the stratified material.

4. A concentrating apparatus including a 100 hydraulic concentrator means for stratifying the material with the fines at the bottom and the middlings at the surface, said hydraulic concentrator having a tailings discharge; and means to wash the upper stratum of 105 middlings from the stratified material, said first-mentioned means constituting the feed for delivering the stratified material to the second-mentioned means.

5. A concentrating table one end of which 110 constitutes the concentrates discharge and having feed means confined to the opposite end of the table from the concentrates discharge, said table having that side opposite the tailings discharge disposed obliquely and 115 having a narrow passage approximately of uniform width extending along said opposite side to direct received material longitudinally toward the concentrates discharge end from said end feed means, riffles on 120 said table obliquely disposed for discharging material to said passage substantially along the complete length of said oblique side, said passage affording unobstructed travel for the material toward the concentrates discharge, the table along said passage being free from wash water and feed means.

6. A concentrating table having an un-washed concentrating surface presenting a 130

longitudinal barrier at a side of the effective total area, and having an end discharge for the concentrates and riffles disposed over said unwashed area and terminating along 5 a line at a short distance from said barrier, there being a straight passage along the barrier between the same and the riffle ends and extending toward the concentrates discharge, along which passage stratification 10 may progress, said riffles being at an oblique angle to said barrier to direct the unwashed material being treated toward said barrier along substantially its whole length; together with feed means to deliver feed material 15 solely to that end of the table opposite the concentrates discharge.

7. A concentrating table having an end concentrates discharge and feed means at the end thereof opposite the discharge for the concentrates, said table narrowing toward 20 the discharge end and presenting a longitudinal barrier at a side of the effective table surface, said barrier extending from said feed means, and riffles oblique to the 25 longitudinal axis of the table to direct the material against said barrier, there being a comparatively narrow unwashed passage extending approximately parallel to said barrier to afford guided longitudinal movement 30 to the received material for stratification and progression toward the concentrates discharge the material forwardly parallel with the barrier.

8. A hydraulic settling table having a 35 concentrates discharge at an end thereof and narrowed toward said end, presenting a longitudinal passage at a side of the effective area of the table, there being a barrier at said side against and along which passage the 40 material may progress toward the narrow discharge end of the table, and a series of concentrating riffles on the table at an angle to said passage and terminating successively on a line approximately parallel to said passage, said terminal line of the riffles extending 45 substantially to the discharge end of said table.

9. A concentrating table having an end 50 concentrates discharge including a barrier oblique to the longitudinal axis of the table, feed means solely at the end of the table opposite the concentrates discharge, and concentrating riffles on the table at an angle to the plane of said barrier, to direct material 55 against the barrier, said riffles terminating short of said barrier so that a restricted longitudinal passage is presented between said barrier and the adjacent ends of the riffles affording a straight path for the undisturbed stratification of the material and 60 the progression of the received material toward the concentrates discharge.

10. A concentrating table including feed 65 means at an end of the table, a barrier oblique to the longitudinal axis of the table

and gradually nearer the longitudinal axis thereof, concentrating riffles on the table at an angle to the plane of said barrier, all of said riffles terminating short of said barrier to direct the material against the barrier for substantially the whole length of 70 the table, there being a narrow longitudinal stratifying passage between said barrier and the discharge ends of said riffles for substantially the complete length of the table 75 and there being a longitudinally disposed tailings discharge at the opposite side of the table from the oblique barrier and passage.

11. A concentrating table narrowed to- 80 ward the end constituting the concentrates discharge and having a barrier oblique to the longitudinal axis of the table, and concentrating riffles on the table at an angle to said barrier of uniform height against 85 which barrier the material is crowded by the riffles, there being a passage between said barrier and the terminals of said riffles for the progress and stratifying of the material along the table toward the narrowed dis- 90 charge end, and feed means at that end of the table opposite the concentrates discharge, the table adjacent to said passage being free from feed means and free from wash- 95 water supply means to leave the material in the passage to stratify undisturbed as it progresses along the passage.

12. A concentrating table narrowed toward its discharge end to present an oblique side opposite the tailings discharge includ- 100 ing a series of concentrating riffles oblique to the longitudinal axis of the table and to first mentioned side, the series comprising 105 riffles extending from points along a trans- 110 verse line adjacent to the feed end of the table, and other riffles extending from points along that side of the table constituting the tailings discharge, said table affording an unwashed longitudinal stratifying passage for the material concentrated between said 115 riffles and extending from the feed end of the table to the narrow discharge end.

13. A concentrating table including a series of concentrating riffles oblique to the longitudinal axis of the table, the series 115 comprising riffles extending from points along a transverse line adjacent to the feed end of the table, and other riffles extending from points along that side of the table constituting the tailings discharge, said table 120 affording along the upper side of the table a longitudinal passage for the material concentrated between said riffles and said riffles terminating at said passage, certain of the concentrating riffles adjacent that end of 125 the table opposite the feed end being at a less angle to the longitudinal axis of the table than those riffles disposed over the major portion of the table.

14. A concentrating table including a 130

- barrier along a side of the table from the feed end to a point adjacent to the opposite end as well as a barrier along the opposite side of the table from a point adjacent to the feed end but extending a less distance than the first-mentioned barrier, there being a tailings discharge between said second-mentioned barrier and that end of the table opposite the feed end; together with concentrating riffles extending from points along a transverse line, adjacent the feed end toward the first-mentioned barrier, and other concentrating riffles extending from points along the second-mentioned barrier toward the first-mentioned barrier, there being a longitudinal passage for the material between the terminals of said riffles and the first-mentioned barrier.
15. A bumping hydraulic concentrating table for concentrating without the use of wash water, one end being the feed end and the opposite end the concentrates discharge, said table presenting generally a triangular form narrowing toward said discharge end and affording a longitudinal passage for the material oblique to the longitudinal axis of the table and substantially from end to end thereof, and concentrating riffles on the table oblique to said passage and delivering the concentrated material to the latter.
16. A concentrating apparatus including a hydraulic settling table having means for stratifying the material without the use of wash water, and a water delivery means between the concentrating table and the discharge for the concentrates to wash off the middlings from the stratified material.
17. A concentrating apparatus including a hydraulic settling table for stratifying the material without the use of wash water, and a clarifier between the concentrating table and the discharge for the concentrates, said clarifier including water delivering means at a side of the clarifier to direct water thereto for washing off the surface stratum, and there being a discharge for the washed-off material at the side of the clarifier opposite the water supply.
18. A concentrating apparatus including a hydraulic settling table for stratifying material, said table narrowing toward the end opposite the feed end, a clarifying area between the narrowed end of the concentrating table and the discharge for the concentrates, there being raised riffles on the concentrating table oblique to the longitudinal axis of the table and a longitudinal side passage along which the material may progress from said concentrating riffles to the narrowed end of the table, and raised riffles on said clarifying area and disposed generally longitudinally of said area; together with a water supply for delivering water to the clarifying area at that side of the table at which said passage is disposed.
19. A concentrating apparatus including a hydraulic settling table having raised stratifying riffles and a clarifier to which the stratified material is delivered from said table, said clarifier including a water delivery pipe at a side of the table to wash off the middlings from the stratified material and a distributing reservoir having an overflow wall constituting a breakwater, there being a discharge for wash material at the opposite side of the clarifying area.
20. A concentrating apparatus including a riffled hydraulic settling table narrowed toward the end opposite the feed end and having a tailings discharge along one side of the table, and a riffled clarifying area between the narrowed end of the concentrating table and the discharge of the concentrates, said clarifying area extending laterally beyond the narrowed end of the table at the side having the tailings discharge and affording a discharge for washed material, there being means to supply water to the clarifying area at the opposite side.
21. A concentrating table presenting oblique concentrating riffles terminating short of a side of the table so that the latter presents a longitudinal side passage to which the riffles deliver, certain of the riffles adjacent to the discharge end of said passage being of decreased length to afford a widening of the passage; together with means to supply water adjacent said passage and adjacent to said riffles of reduced length.
22. A concentrating table including a barrier oblique to the longitudinal axis of the table along a side of the table, oblique stratifying riffles extending from points along a transverse line adjacent to the feed end of the table and terminating short of said barrier to crowd the stratified material against said barrier as well as riffles extending from points along the opposite side of the table from said barrier and terminating short of the latter; together with feed means disposed between the first-mentioned riffles and said barrier.
23. A concentrating apparatus including a hydraulic settling table having means to stratify the material and narrowed toward the discharge end, a clarifying area between the narrowed end of said table and the discharge for the concentrates to which the clarifying area the stratified material is delivered, said clarifying area presenting a surface continuous with the surface of said concentrating table, and means to supply water to the clarifying area at a side thereof for washing off the surface stratum of the stratified material.
24. A riffled concentrating table narrowed

- toward that end constituting the discharge for the concentrates and having a longitudinal passage adjacent to that side of the table opposite the side over which the tailings discharge and therefore remote from said tailings discharge, feed means confined to that end of the table opposite the concentrates discharge, the table being without feed means along said passage, and an un-washed riffled surface extending over substantially the complete table except said passage, the riffles being oblique to discharge to said passage.
25. A concentrating table having a tailings discharge along one side, one end of the table constituting the discharge for concentrates, feed means confined to that end of the table opposite the said discharge, the side of the table to which said passage is adjacent being without feed means and without wash-water supply means, said table having a longitudinal passage along and adjacent said opposite side, and having a main area provided with raised stratifying riffles oblique to said passage and directing material to said passage, said riffled area being narrower toward the discharge end of the table to cause the tailings to be crowded to and over said tailings discharge, a second riffled area beyond the main riffled area and beyond said tailings discharge and positioned to receive the stratified material from said narrowed end of the table, and means beyond the main riffled area and beyond the tailings discharge to supply wash water for washing off the middlings from the stratified material of said second riffled area.
26. A concentrating table having feed means confined to that end of the table opposite the discharge end, said table presenting a longitudinal stratifying passage extending from the feed end along the side of the table opposite the tailings discharge, riffles on said table at an angle to direct the material to said passage, the table being free of feed means along said passage and free of wash-water supply means to leave the material progressing along said passage undisturbed by a cross feed of material or by washing water.
27. A concentrating table having feed means confined to that end of the table opposite the discharge end, said table presenting a longitudinal stratifying passage extending from the feed end along the side of the table opposite the tailings discharge, riffles on said table at an angle to direct the material to said passage, the table being free of feed means along said passage and free of wash-water supply means to leave the material progressing along said passage undisturbed by a cross feed of material or by washing water; together with a riffled clarifying area beyond said passage between

the same and the discharge for the concentrates to which last-mentioned area the stratified material is directed from said passage, and means to direct washing water to said clarifying area for washing off the middlings.

28. A concentrating table having oblique riffles and having a longitudinal passage along that side of the table opposite the tailings discharge into which passage the material from said riffles is crowded along which passage the material may progress and stratify, feed means solely at that end of the table opposite the concentrates discharge, the table being free of feed means and free of water supply means along said passage, thereby leaving the material moving along said passage undisturbed by cross feed or wash water.

29. A concentrating table having an un-washed riffled concentrating surface presenting a longitudinal barrier at a side of the table opposite the tailings discharge, a longitudinal passage along said opposite sides into which the material from the riffles is directed, and feed means at the end of the table opposite the discharge for the concentrates and adjacent to the side of the table having said passage, there being an unriffled distributing area adjacent to the rear end of said passage and between the feed means and the riffles.

30. A concentrating table having a tailings discharge at a side thereof, and riffles rising to their greatest vertical dimension at the side opposite the tailings discharge and presenting transversely a compound curve at the side toward the tailings discharge.

31. In a concentrating method; producing a stratification of the concentrated material by hydraulic settling and washing off the surface material from the stratified material.

32. In a concentrating method, producing a stratification of the material with the middlings at the surface, and the tailings eliminated and then washing off the middlings.

33. In a concentrating method, producing a stratification of wet ground material, and elimination of tailings therefrom by subjecting the material to a jarring action on a concentrating table in the absence of wash water, and then washing off the top stratum.

34. In a concentrating method, the steps of stratifying without wash water on a concentrating table, the concentrates of wet ground material, while causing the stratified material to progress forwardly onto a narrow area thereof to cause the tailings to be crowded off, and washing off the top stratum of the stratified concentrates.

35. In a method of concentrating ores on

- a riffled table, the steps of feeding material to the table, giving such movements to the material over the riffled surface so as to cause stratification of the material to take place between the riffles, discharging the 15
5 place between the riffles, discharging the stratified material to an unriffled restricted area, imparting movement to the material along said restricted unriffled area and giving movement to the material along said restricted unriffled area in a manner to effect progressive stratification.
- 10 36. In a method of concentrating ores on a riffled table, the steps of feeding material to the table, giving such movements to the material over the riffled surface so as to cause stratification of the material to take place between the riffles, discharging the 15
10 stratified material to an unriffled restricted area, imparting movement to the material along said restricted unriffled area in a manner to further stratify the material, with the middlings forming the upper stratum, and 20 then washing off said upper stratum from the stratum beneath.
